CLAIM

The ornamental design for a lidded container, as shown and described.

DESCRIPTION

FIG. 1 is a top front perspective view of a lidded container; FIG. 2 is a bottom front perspective view of the lidded container of FIG. 1;

FIG. 3 is a front view of the lidded container of FIG. 1; FIG. 4 is rear view of the lidded container of FIG. 1;

FIG. 5 is a left side view of the lidded container of FIG. 1; FIG. 6 is a right side view of the lidded container of FIG. 1;

FIG. 7 is a top view of the lidded container of FIG. 1; FIG. 8 is a bottom view of the lidded container of FIG. 1; FIG. 9 is a top front perspective view of another lidded container;

FIG. 10 is a bottom front perspective view of the lidded container of FIG. 9; FIG. 11 is a front view of the lidded container of FIG. 9; FIG. 12 is a rear view of the lidded container of FIG. 9; FIG. 13 is a left side view of the lidded container of FIG. 9; FIG. 14 is a right side view of the lidded container of FIG. 9;

FIG. 15 is a top view of the lidded container of FIG. 9; and, FIG. 16 is a bottom view of the lidded container of FIG. 9. The dot dash broken lines show boundaries that form no part of the claimed design.

1 Claim, 16 Drawing Sheets
